UNITED STATES PATENT OFFICE.

EMBURY A. HITCHCOCK, OF COLUMBUS, OHIO, AND NORMAN L. HAYDEN,
OF NEW YORK, N. Y.

FEED-WATER HEATER.

SPECIFICATION forming part of Letters Patent No. 683,762, dated October 1, 1901.

Application filed January 10, 1901. Serial No. 42,748. (No model.)

To all whom it may concern:

Be it known that we, EMBURY A. HITCHCOCK, of Columbus, in the county of Franklin, State of Ohio, and NORMAN L. HAYDEN, of New York, in the county of New York and State of New York, have invented certain new and useful Improvements in Feed-Water Heaters; and we do hereby declare the following to be a full, clear, and exact description of the invention, such as will enable others skilled in the art to which it appertains to make and use the same.

This invention contemplates certain new and useful improvements in feed-water heaters.

The primary object is to heat feed-water under pressure by the intermixing of live steam, so that all impurities will be separated from the water and the circulation will be greatly augmented, thereby increasing the efficiency of the boiler and permitting of a great saving of fuel. By the means employed the temperature of the feed-water while under pressure in passing through the delivery-pipe from a feeder may be raised to 250° or more.

A further object is to provide improved means for heating the feed-water in the delivery-pipe by the introduction of live steam without obstruction by back pressure.

The invention will be hereinafter fully set forth, and particularly pointed out in the claims.

In the accompanying drawings, Figure 1 is a view showing the application of our invention. Fig. 2 is an enlarged vertical sectional view of the heater.

Heretofore various means and methods have been employed for heating feed-water previous to its discharge into a boiler, for the purpose, first, of avoiding waste of fuel consequent upon the introduction of water into the boiler at a low temperature; secondly, to remove all impurities and scale-forming substances, and, thirdly, to improve the circulation of water in the boiler. In some instances the feed-water has been heated to the required extent by using steam-injectors as boiler-feeders in connection with boilers carrying high steam-pressure; but the required temperature in the water for producing precipi-

tation cannot be secured where a comparatively low pressure of steam is maintained. By our present invention we are enabled to secure the required temperature in the delivery-pipe of injectors of various capacities and under different conditions and also in the water-discharge of an ordinary feed-pump even with low steam-pressure.

Referring to the drawings, 1 designates the boiler; 2, the steam-dome; 3, the steam-pipe leading from the latter; 4, an injector; 5, the delivery-pipe or feed-main; 6, a feed-pump, and 7 a branch delivery-pipe leading from the discharge of the pump to pipe 5. In this branch and also in the delivery-pipe 5, between the branch and the injector, are ordinary check-valves 8 and globe-valves 9 and 10, one of which latter is closed when the other is open, thus permitting feeding by either the injector or pump. Our invention being applicable for heating water under pressure regardless of whether it be delivered by an injector or a pump, we have shown both forms of feeders connected to a common delivery-pipe.

12 designates the heater, which is located in the delivery-pipe intermediate the injector or pump and the boiler. It has the general appearance of a steam-injector, but differs from such a machine both in construction and operation. The casing 13 is formed at one end with a water-inlet 14, in line with which are a water-inlet tube 15 and a combining and delivery tube 16, the cross-sectional area of the inlet end of the combining-tube being considerably greater than the cross-sectional area of the discharge end of the water-inlet tube. The opposed ends of the water and combining tubes are within the steam-chamber 17, into which steam is supplied through pipe 3. The water travels through the delivery-pipe 5 at a high rate of speed, and in passing through the water-inlet tube of the heater and thence into the combining-tube a vacuum is created about the inlet end of the latter, resulting in the drawing of the steam in with the water, the action of which is to heat the latter before it enters the boiler (or it may be a feed-water purifier intermediate the heater and boiler) to a temperature of 250° or over even with low steam-pressure.

We have found in actual practice that when the water is admitted to the heater under pressure from the injector or pump a vacuum of twenty (20) inches or more is created at the 5 point of entrance of steam to the heater. The momentum of the delivered water is so great that it will be heated and discharged even as against a very great back pressure in the discharge-pipe. The momentum and pressure 10 of the feed-water are such that it will not only overcome the back pressure from the boiler, but also force the water through various resistances employed for filtration purposes.

From what has been said the advantages of 15 our invention are apparent. It will be seen that we have provided means whereby water under pressure in passing to a boiler, either directly or indirectly, as first through a filter, may be heated by live steam to such an extent as to precipitate all foreign substances 20 and at the same time overcome back pressure.

We claim as our invention--

1. The combination with a feed-water pipe 25 for a boiler, and a feeder for feeding the water under pressure, of means, in said pipe intermediate the feeder and the discharge end, for allowing live steam to be entrained by the water in said pipe while under pressure and 30 before its discharge into the boiler.

2. The combination with a feed-water pipe for a boiler, and a feeder for feeding the water under pressure, of a heater having a steam-chamber to which live steam is supplied, and 35 passage-ways within such heater through

which the water under pressure will travel, said passage-ways allowing the water in its transit therethrough to entrain the steam from such chamber, as set forth.

3. The combination with a feed-water pipe 40 for a boiler, and a feeder for feeding the water under pressure, of a heater having a steam-chamber, a water-inlet tube at one end opening into said chamber, a combining and delivery tube leading from said chamber, the 45 receiving end of said combining-tube being of greater cross-sectional area than the discharge end of the water-inlet tube, steam in said chamber being entrained by the water in its passage from the water-inlet tube to the 50 combining-tube, as set forth.

4. The combination with a feed-water pipe for a boiler, and an injector to which said pipe is connected, of a heater located in said pipe comprising a casing, a steam-pipe opening 55 into a steam-chamber in said casing, and tubes within said casing forming passage-ways for the water under pressure and having communication with said steam-chamber so that the water in its passage through said 60 tubes will entrain the steam from said chamber.

In testimony whereof we have signed this specification in the presence of two subscribing witnesses.

EMBURY A. HITCHCOCK.
NORMAN L. HAYDEN.
